United States Patent Office

Des. 203,813
Patented Feb. 22, 1966

203,813

OPERATING HANDLE FOR A VENDING MACHINE OR SIMILAR ARTICLE

Iber C. Courson, Longmeadow, Mass., assignor to Westinghouse Electric Corporation, a corporation of Pennsylvania

Filed Apr. 28, 1965, Ser. No. 85,012

Term of patent 14 years
(Cl. D10—8)

FIG. 4.

FIG. 2.

FIG. 1.

FIG. 3.

FIG. 5.

FIGURE 1 is a front view of an operating handle for a vending machine or similar article;

FIG. 2 is a side view as seen to the left of FIGURE 1;

FIG. 3 is a side view as seen to the right of FIGURE 1;

FIG. 4 is a top view as seen from above FIGURE 1; and

FIG. 5 is a bottom view as seen from below FIGURE 1. The dominant features of my new design reside in the portions shown in full lines.

I claim:

The ornamental design for an operating handle for a vending machine or similar article, substantially as shown and described.
